UNITED STATES PATENT OFFICE.

GEORGE R. TOMB, OF LORAIN, OHIO, ASSIGNOR TO THE PNEUMATIC RAILWAY EQUIPMENT COMPANY, OF CLEVELAND, OHIO, A CORPORATION.

TROLLEY.

SPECIFICATION forming part of Letters Patent No. 718,678, dated January 20, 1903.

Application filed May 21, 1902, Serial No. 107,324. (No model.)

To all whom it may concern:

Be it known that I, GEORGE R. TOMB, a citizen of the United States, residing at Lorain, in the county of Lorain and State of Ohio, 5 have invented new and useful Improvements in Trolleys, of which the following is a specification.

My invention relates to improvements in trolleys; and the object of the same is to construct a spring-actuated trolley which will be provided with automatic means for pulling the trolley-pole down whenever the sheave thereon jumps the wire.

The novel construction employed by me in carrying out my invention is fully described in this specification and claimed, and illustrated in the accompanying drawings, forming a part thereof, in which—

Figure 1 is a vertical longitudinal section 20 of the means for operating the trolley-pole, the trolley being in engagement with the wire. Fig. 2 is a plan view of the same, partly in section, with the trolley down. Fig. 3 is a vertical longitudinal section through the valve-box 25 with the valve closed. Fig. 4 is a side elevation of the same. Fig. 5 is a section on the line 5 5, Fig. 4. Fig. 6 is a detail section of the valve 37 closed. Fig. 7 is a similar view, the valve open.

Like numerals of reference designate like parts in the different views of the drawings.

The numeral 1 designates a rotatable horizontal platform, which is mounted on a vertical spindle 2^a, passing through a base-plate 35 2. Standards 3 are mounted on the platform 1, and pivoted thereto by a cross-pin 4 is a trolley-pole 5, which is prolonged beyond the pin to form an arm 6. A flange 7 is formed integral with the platform 1 and in combination with two lugs 8 serves to support two parallel guide-rods 9, on which a cross-head 10 is slidingly mounted. Spiral springs 11 surround the guide-rods 9 and bear at one end on the cross-head 10 and at their other ends 40 on adjusting-nuts 12, which serve to regulate the tension of the springs 11. A connecting-rod 13 connects the cross-head 10 and the arm 6 on the trolley-pole, which is thereby held up in contact with the wire by the expansion 45 force of the springs 11. A spring 14 is mounted on the rod 13 and bears at one end on the

cross-head 10 and at the other end on an adjusting-nut 15, mounted on a threaded portion 13^a of the connecting-rod 13.

A cylinder 16 is headed on the flange 7 and 55 is secured thereto by bolts passing through a rim 17, secured on the end of the cylinder 16. A piston 18 is snugly mounted in the cylinder 16, and hinged thereto is a piston-rod 19, which is oppositely connected to an adjustable clip 20, embracing the trolley-pole 5 and firmly clamped thereto.

Mounted in the flange 7 and extending into the forward compartment of the cylinder 16 are buffers comprising stems 21, carried by 65 pistons 22, snugly fitting cylinders 23, provided with heads 24, apertured at 25 to permit the outflow of air. Springs 26 bear on the pistons 22 and together with the air in the cylinders serve to retard the movement 70 of the pistons 22 and serve as buffers for the piston 18. These buffers keep the trolley-pole 5 from being brought down too suddenly.

A T-pipe 27 is connected by one arm 27^a to the rear head of the cylinder 16. The other 75 arm 27^b of the T is capped at 28, and slidingly mounted within this arm is a cup-valve 29, which is normally held against the cap by a coiled spring, which bears on the bottom of the cup. A stem 30 is connected at one end 80 to the bottom of the cup 29 and at the other end to a flexible member 31, which is connected to a coiled spring 31^a, which is attached to the piston 18. The stem 27^c is connected to a pipe 32, which is passed down 85 through the spindle 2^a and connects with a cylinder 33, carried by the car and containing air under pressure. A ball-joint 34 is formed in the pipe 32 and leaves the platform 2 free to turn. By means of the arrangement just described when air is admitted into the pipe 32 it is free to flow into the cylinder 16 until the piston 18 runs forward, when the valve 29 will be operated to close the mouth of the stem 27^c and almost entirely 90 shut off the flow of air into the cylinder 16. A small quantity of air can still pass into the cylinder 16, so the action of the cup-valve 29 is that of a reducing-valve to clear the flow 95 of air.

A box 35 is mounted in the motorman's vestibule on the car and surrounds a valve-cas-

ing 36, connected in the pipe 32. A valve 37 is mounted in the casing and has a stem 38, bearing an arm 39, carrying a pin 39^a. A spring 40 is connected at one end to the arm 39 and at the other end to the box 35 and serves to open the valve when the arm 39 is released. A trip-lever 41 is fulcrumed on a pin seated in a standard 42, footed on the box 35. The upper short arm 41^a is rounded off on one side to adapt it to be engaged by the pin 39^a and be displaced. A roller 43 is carried by an armature 44, mounted in guides 45 and located opposite the poles of a pair of electromagnets. The coils 46 of the electromagnets are connected in series with the trolley-pole. The armature 44 is located in position to be attracted by the magnets to raise the roller 43 up into engagement with the long arm 41^b of the lever 41. When the current through the coils 46 is broken, the armature will drop and cause the roller to release the trip-lever 41 to release the arm 39 and permit the spring 40 to open the valve 37 and allow the air to flow to the cylinder 16.

25 The slide 47 is mounted in the guides in the box 35 and carries stops 48, which limit its movement. A flexible member 49 is connected at one end to the slide 47 and at the other to the arm 39. A conductor's cord 50 is connected to the upper end of the slide 47 and serves to operate the slide to pull it up to actuate the arm 39 to close the valve 37 and bring the pin 39^a into engagement with the trip-lever 41 to set it. Simultaneously with 30 the closing of the valve 37 a port 37^a is opened to the atmosphere, which permits the air in the upper portion of the pipe 32 to escape. As soon as the air in the pipe 32 has been released the pressure of the confined air in the 35 cylinder 16 will act on the cup-valve 29 and overcome the force of the spring 31^a and the air in the rear of the cup which will leak out alongside the valve and open the valve 29 to release the air in the cylinder and permit the 40 trolley to rise up into engagement with the wire.

45 A plug 51 is provided for insertion under the armature 44 when it is desired to keep it from dropping and releasing the trip to open the valve 37 when the current passing through the coils 46 is broken. A switch 52 is also connected in circuit with the coils 46 to serve to break the circuit through the coils 46 to open the valve 37 to pull down the trolley-pole 5 whenever desired.

50 In operation the trolley is normally in engagement with the wire, a current is passing through the coils 46, the trip 41 is in engagement with the roller on the armature 44 and 55 with the pin on the arm 39, the valve 37 is closed against the flow of air from the cylinder 33 into the cylinders 16 via the pipe 32, and the cylinder 16 is open to the atmosphere. If the trolley 5 should now jump off the wire, 60 the circuit through coils 46 is broken and the armature 44 is released, which releases the trip 41 and permits the spring 40 to open the

valve 37 and permit the air from the cylinder 33 to flow into the cylinder 16 to actuate the piston 18 and pull down the trolley 5. By 70 now pulling the cord 50 the valve 37 can be closed and the port 37^a be opened and the trolley-pole 5 released. The slide 47 is held up by means of the cord 50 until the trolley-pole 5 engages the wire, when a circuit will 75 be established through the coils 46, which will raise the roller on the armature 41 up into engagement with the trip 41 and hold the valve closed, after which the slide 47 is pulled down.

80 I do not wish to be limited as to details of construction, as these may be modified in many particulars without departing from the spirit of my invention.

Having described my invention, what I 85 claim as new, and desire to secure by Letters Patent, is—

1. In a device of the class described, the combination with a cylinder provided with air connections, a valve mounted to control 90 the flow of air into said cylinder, a piston mounted in said cylinder and connected to operate said valve, a trolley-pole, a piston-rod pivoted to said piston and to said trolley-pole, parallel guides, a cross-head mounted 95 on said guides, springs mounted in said guides and bearing on said cross-head, a connecting-rod connecting said cross-head and said trolley-pole, substantially as described.

2. In a trolley, the combination of a trolley-pole, means for holding said trolley up in engagement with the conductor, a cylinder provided with a piston, means for connecting said piston and said trolley-pole, a pipe connected to said cylinder, a valve mounted in said 105 pipe to control the supply of air thereto, and means connecting said valve and said piston, substantially as described.

3. In a trolley, the combination of a trolley-pole, means for holding said trolley-pole in engagement with the conductor, a cylinder provided with a piston connected to said trolley-pole, a T connected by one arm to said cylinder, and a pipe connected to the stem of said T, a valve slidably mounted in the arms of said T, a spring bearing on said valve to hold it in its normal open position, a flexible member connecting said piston and said valve, substantially as described.

4. In a trolley, the combination of trolley-pole, means for holding said trolley-pole in engagement with the conductor, a cylinder provided with a piston and having air connections, a slidably-mounted valve arranged to control the admission of air to said cylinder, and means for connecting said valve and said piston, substantially as described.

5. In a trolley, the combination with a trolley-pole, a cylinder provided with air connections, a piston mounted in said cylinder and connected to said trolley, means for controlling the flow of air into said cylinder, and buffers mounted in said cylinder and located to check the movement of said piston to keep

said trolley from being pulled down too quickly, substantially as described.

6. In a device of the class described, the combination with a trolley, of a cylinder provided with a piston connected to said trolley, a pipe connected to said cylinder, a valve mounted in said pipe, an electromagnet in circuit with said trolley and provided with an armature bearing a roller, a lever connected to operate said valve, and a trip mounted to engage said roller and said lever

when said armature is attracted by said magnet, said roller being arranged to release said trip when the circuit through said magnets is broken, substantially as described. 15

In testimony whereof I have hereunto set my hand in presence of two subscribing witnesses.

GEORGE R. TOMB.
